UNITED STATES PATENT OFFICE.

MAURICE G. BENEDICT, OF DETROIT, MICHIGAN.

DESIGN FOR AN OIL HEATING-STOVE.

SPECIFICATION forming part of Design No. 21,853, dated September 6, 1892.

Application filed July 30, 1892. Serial No. 441,751. Term of patent 7 years.

To all whom it may concern:

Be it known that I, MAURICE G. BENEDICT, a citizen of the United States, residing at Detroit, in the county of Wayne, State of Michigan, have invented a certain new and original Design for Oil Heating-Stoves; and I declare the following to be a full, clear, and exact description of the same, such as will enable others skilled in the art to which it pertains to make and use the same, reference being had to the accompanying drawing, which forms a part of this specification.

The drawing shows in perspective a stove made after my design.

15 In the drawing appear the front and one side of the stove. The rear of the stove is similar to the front, omitting only the foot-rail. The two sides of the stove are alike.

The entire stove may be divided for the 20 purposes of description into the base D, the burner-chamber E, the heating-drum F, and the top G. The base may be subdivided into an ornamented leg-frame A, a tank-chamber B, and the cover C thereto extending nearly

25 flat inward until it meets the walls of the burner-chamber E. The leg-frame A consists of four legs *a b c*, with the connecting frame-pieces *e f* ornamented with scrollwork, as shown in the drawing. The tank-chamber B

30 is square, with one ring of horizontal flutings or corrugations *d* around the upper edge above the middle line and another ring of horizontal flutings or corrugations *g'* around the lower edge. The cover part C to the base is

35 square with rounded corners and is ornamented with scrollwork in relief. At each corner rises an ornamented flue-tube *H I K*, of which the outer wall is rounded in horizontal cross-section and curves vertically with

40 a cyma curve and terminates in a knob or boss surmounted by a representation of an open flower *h i k*. Resting on the four flues is a circular chamber R, the visible walls of which are oval in vertical cross-section.

On each side of the stove between the ornamental flues is a deep-seated mica-glazed light-opening O O, and from the extreme outer edges of the flues to the edges of the light-opening the walls of the flues are ornamented with scrollwork. The under wall of the circular chamber R from its extreme outer edge to the edge of the light-opening is ornamented with radial corrugations, giving to the light-opening the appearance of depth and to the light inclosed within the appearance of distance. The upper exposed side of the circular chamber R is smooth, and above the circular chamber is a cylindrical heating-chamber F, and this is surmounted by the top G, dome-shaped and supporting at its apex an 60 urn *r*. Around the bottom of the dome-shaped top is a row of holes, and above them a second row of long oval holes wider at the bottom than at the top.

It will be seen that while the entire stove 65 is very much broken in outline its salient features are the square base, the deep-seated cavernous light-openings in the burner-chamber, and the cylindrical dome-capped drum.

What I claim is—

The design for an oil heating-stove, consisting of an ornamented square leg-frame, a square tank-chamber, a burning-chamber having deeply-seated light-openings, the side and bottom approaches to said openings being ornamented with scrollwork, the meeting edges of contiguous openings being rounded and finished vertically in a cyma curve terminating at its upper end with an open flower, a round heating-chamber, and a dome-shaped 75 top, substantially as shown and described.

In testimony whereof I sign this specification in the presence of two witnesses.

MAURICE G. BENEDICT.
